MICHAEL MEANY, JOHN McGINNIS, AND WILLIAM CUNNINGHAM, OF BROOKLYN, NEW YORK.

Letters Patent No. 101,293, dated March 29, 1870.

IMPROVEMENT IN CORNICE-MOLD.

The Schedule referred to in these Letters Patent and making part of the same.

To all whom it may concern:

Be it known that we, MICHAEL MEANY, JOHN McGINNIS, and WILLIAM CUNNINGHAM, of Brooklyn, in the county of Kings and State of New York, have invented a new and improved Mold for Cornices; and we do hereby declare that the following is a full, clear, and exact description thereof, which will enable others skilled in the art to make and use the same, reference being had to the accompanying drawings forming part of this specification, in which—

Figure 1 represents a side view of our improved mold for cornices.

Figure 2 is a plan or top view of the same.

Similar letters of reference indicate corresponding parts.

This invention relates to cornice-molds adapted to rooms, halls, &c., whose corners make varying angles; and consists in certain improvements thereon, which will be specified hereinafter.

The frame consists of two plates, A B, hinged together at their contiguous ends by a pin, *a*, while their other ends carry curved plates, *b b*, which are formed on circles that are described from the pin *a*, as center. The plates A B can be swung any distance apart, or together, to form an angle of suitable size.

To the projecting pivot-pin *a* is secured a plate, C, which extends to the arc formed by the parts *b b*, and which, at its outer end, carries a screw, *d*, that projects through slots in the plates *b*.

The pattern-plate D, whose edge is cut out to produce the requisite molding, is secured between two cheeks of the plate C, and is held therein by screws, *e*, or their equivalents. It is evident that the plate D on C, can be set at any angle to the one of the sides A B, which is moved along and parallel with the wall. It is also clear that either one of the sides A B can be thus used on the wall, and that, therefore, the motion of the device can be readily reversed.

The pattern-plate should be set at such an angle as to produce the proper miter; and the two sides should also be set at the angle of the corner, so that, when the outer plate strikes the wall, the miter will have been produced. The pattern-plate can be readily removed and replaced, and the frame be used for all the various kinds of cornices. The screw *d* locks the parts A B C in the various desired angles.

Having thus described our invention, We claim as new and desire to secure by Letters Patent—

The construction and arrangement of independent cheek-plate C, adjustable pattern-plate D, and set-screws *d e*, as and for the purpose specified.

MICHAEL MEANY.

JOHN McGINNIS.

WILLIAM CUNNINGHAM.
